OIL BURNER

Lynn O. Selby, Cromwell, Conn., assignor to The
Sparmal Engineering Corporation, a corpora-
tion of Connecticut

Application November 29, 1939, Serial No. 306,671

7 Claims. (Cl. 158—86)

My invention relates to oil burners.

It has among its objects to provide an improved oil burner, and, more particularly, to provide such an improved burner of the so-called combined power and distillate type. A further object of my invention is to provide an improved burner base for such combined burners wherein, through an improved structure of the power burner and associated distillate burner, it is made possible materially to increase the capacity of the power burner. A further object of my invention is to provide such an improved construction wherein through an improved arrangement it is made possible to dispose the vaporizing chamber of the power burner in the space previously occupied by the vaporizing chamber of the distillate burner, in such manner as thus materially to increase the capacity of the power burner and the quantity of oil capable of being vaporized thereby in a given time interval, while also disposing the vaporizer for the distillate burner in an improved location enabling the latter to continue to function satisfactorily as a heating means for the power burner during starting and operation of the latter. These and other objects and advantages of my improved construction will, however, hereinafter more fully appear.

In the accompanying drawing, I have shown for purposes of illustration one embodiment which my invention may assume in practice.

In this drawing:

Figure 1 is a vertical sectional view of a burner equipped with my improvements;

Fig. 2 is a plan view of the burner base, the shells being omitted and the section on which Figure 1 is taken being indicated on line 1—1, while parts are broken away to facilitate illustration;

Fig. 3 is a section on line 3—3 of Figure 2, but with the shells shown thereon and broken away to facilitate illustration;

Fig. 4 is a detail section on line 4—4 of Figure 2, and

Fig. 5 is a semi-diagrammatic view of a form of heater installation equipped with my improvements.

In this illustrative construction, I have shown a burner base, generally indicated at 1, provided with usual inner and outer grooves 2 and 3 for the distillate burner and usual starting wicks 4 in these grooves and perforate shells 5 defining combustion spaces above the grooves and having usual air passages 6 and 7 and usual cover plates, or rings, 8, 8a, while the inner and outer grooves 2 are adapted to communicate with one another

through any suitable radially located passages, as, for example, the passage 4a. As illustrated, this distillate burner construction has a power burner, generally indicated at 9, of an improved construction axially located therein and improved vaporizing means for both this power burner and the distillate burner disposed in improved locations and functioning in an improved manner, as hereinafter more fully described.

Referring more particularly to the power burner 9, it will be noted that the same is of an improved construction and of increased dimensions and has an enlarged vaporizing chamber disposed in the space previously occupied by the vaporizing chamber for the distillate burner. More particularly, it is provided with a vaporizing chamber 10 in the burner base 1, which, while annular and shallow, is of substantially increased horizontal cross section as compared with prior

constructions. Thus, it is made possible materially to increase the area of the bottom of this chamber and the resultant capacity thereof to vaporize an increased quantity of oil delivered thereto through a usual carbon leg or vaporizer

11, while maintaining the maximum depth of oil during starting within the desired limits. While, if desired, the bottom of this chamber 10 may be disposed in the plane of the bottoms of the grooves 2 and 3, the bottom of the same is preferably disposed slightly below the bottoms of

these grooves, as illustrated, in such manner as thereby further to increase the vaporizing capacity of this chamber 10. Further, it will be noted that this vaporizing chamber 10 is disposed coaxially around an upwardly directed axial air tube 12 supplied with air under pressure through an axial supply pipe 13; this air tube herein also being of increased diameter, as compared with prior constructions, and having the supply pipe 13 thereto also of increased diameter.

If desired, this pipe 13 may have the passage means therein of the same diameter as the inner diameter of the tube 12, but preferably the inside diameter of the pipe 13 is slightly less than the inside diameter of the tube 12. Also, in this construction a baffle ring 14 is supported on the outer walls 15 of the vaporizing chamber 10 and within an imperforate, combustion chamber forming tube 16 extending up through the shells 5 and having an outlet 17 at the top thereof within the cover plate 8. While this baffle ring may, if desired, have an axial opening 18 of substantially the diameter of the air passage through the tube 12, preferably the opening

18 in this ring is slightly larger than the air passage through the tube 12.

In this construction, the distillate burner is provided with vaporizing means located in an improved location, as compared with prior combined distillate and power burners of this type. More particularly, it will be observed that a vaporizing chamber 19 is provided in the burner base 1 and transversely disposed between the grooves 2 and 3, in such manner as to connect the same while providing for the distribution of the vapor from this chamber to both grooves. Herein, the chamber 19 has a carbon leg or vaporizer 20 connected to the bottom thereof midway between the inner and outer ends of the chamber and the wicks 4. While, if desired, this vaporizing chamber may be provided in the form of a transverse passage in base casting 1 between the grooves, preferably, in order to permit ready access to the chamber 19 and to facilitate cleaning, it is provided with a removable cover plate 24 which closes this vaporizing chamber 19, while underlying the two inner shells. Here attention is also directed to the fact that this vaporizing chamber 19 is disposed symmetrically with the radial passages 4a in such manner that with the vaporizing chamber and two such passages 4a, vapor generated during starting in the chamber 19, or generated in the carbon leg 20 during operation of the burner, may pass freely between the grooves 2 and 3 and effect an equal distribution of the vapor as a result of the draft between the shells.

In the use of my improved construction, it will be understood that the distillate burner is ignited in any usual manner, and that the same brings the vaporizing chamber 10 of the power burner to a suitable vaporizing temperature, and that the distillate burner maintains the same at this temperature in a usual manner. Further, it will be understood that when air under pressure is admitted to the tube 12, this air entrains the vapor rising in the vaporizing chamber 10 and creates a combustible mixture which ignites above the outlet of the tube 12, the baffle ring 14 in the path of the rising vapor also assisting in producing an effective mixture. It will also be understood that the flame extending up through the combustion chamber within the tube 16 is, as usual, blue at its base and to the top of this tube, and white above the latter, in such manner that the blue or heating flame within the tube acts further to heat the vaporizing chamber 10, while the white or radiant flame above the end of the tube 16 is adapted for effective heating purposes. In Figure 5 I have shown my improved combined burner arranged in a usual manner in the fire box 22 of a usual steam, hot water, or air heater 23, the same being enclosed within a usual casing 24 and provided with air through a suitable air conduit 25 connected to a blower 26, while oil to the carbon leg 20 of the distillate burner is supplied through a pipe 27 and oil to the carbon leg 11 of the power burner is supplied through a pipe 28. Both of these pipes 27 and 28 are connected as usual to a constant level float chamber 29 also carrying usual metering valves 30 and 31 establishing the desired maximum flows from this chamber to the distillate burner and power burner, respectively.

As a result of my improved construction, it is made possible very substantially to increase the capacity of the power burner as compared with prior constructions and without disturbing the

automatic starting of the power burner upon the admission of oil to the carbon leg 11 and air under pressure through the pipe 13. Further, it is found that the distillate burner continues satisfactorily to function to maintain the vaporizing chamber 10 of the power burner at vaporizing temperatures, both during the operation of the power burner and when the latter burner is shut down, so that the power burner may be started at any time upon resumption of oil and air supplies thereto. It will further be evident that both burners will continue to be controlled by the float valve mechanism 29 in such manner as to maintain a predetermined maximum level of oil therein when starting both burners, while it will also be clear that during the operation of both burners, each will continue to cooperate as desired, in such manner that the liquid oil supplied through the connections 27 and 28 is so heated by the burner base 1 as to enter the vaporizing chambers 10 and 19 in the form of vapor during normal operation.

While I have herein specifically described one form which my invention may assume in practice, it will be understood that the same has been shown for purposes of illustration, and that my invention may be modified and embodied in other forms without departing from its spirit or the scope of the appended claims.

What I claim as new and desire to secure by Letters Patent is:

1. In a combined distillate and power burner, a burner base having coaxial communicating inner and outer distillate burner grooves, a vaporizing chamber for supplying vaporized fuel to said grooves and located outside the lateral limits of said inner groove and air supply passage means extended upwardly through said base, axially disposed communicating power burner flame and pressure air passage forming means and having the former extending above the base and within said distillate burner, and a power burner vaporizing chamber maintained at a fuel vaporizing temperature by said distillate burner and surrounding said pressure air passage means and communicating with said flame passage means and having its outer wall adjacent said inner groove.

2. In a combined distillate and power burner, a burner base having coaxial communicating inner and outer distillate burner grooves, a vaporizing chamber for supplying vaporized fuel to said grooves and located outside the lateral limits of said inner groove and air supply passage means extended upwardly through said base, axially disposed communicating power burner flame and pressure air passage forming means and having the former extending above the base and within said distillate burner, and a power burner vaporizing chamber maintained at a fuel vaporizing temperature by said distillate burner and surrounding said pressure air passage means and communicating with said flame passage means, said air passage means for said grooves including annularly disposed air supply means within said inner groove and having an inner wall formed by the outer wall of said vaporizing chamber and flame passage means.

3. In a combined distillate and power burner, a burner base having coaxial communicating inner and outer distillate burner grooves, a vaporizing chamber for supplying vaporized fuel to said grooves and located outside the lateral limits of said inner groove and air supply passage means including an annular air passage inside the in-

ner groove, axially disposed communicating power burner flame and pressure air passage forming means and having the former extending above the base and within said distillate burner, and a power burner vaporizing chamber maintained at a fuel vaporizing temperature by said distillate burner and surrounding said pressure air passage means and communicating with said flame passage means and having its outer wall forming the inner wall of said annular air passage.

4. In a combined distillate and power burner, a distillate burner including a base having an annular fuel groove and means outside the lateral limits of said groove for supplying vaporized fuel thereto, means forming a combustion space above said groove, and means for supplying air to the flame in said space, and a power burner axially disposed in said base including communicating flame and pressure air passage forming means and having said flame passage means extending above said base and within said distillate burner, and also having a vaporizing chamber maintained at a fuel vaporizing temperature by said distillate burner and surrounding said air passage forming means and discharging vapor upwardly into said flame passage means, said vaporizing chamber being disposed in substantially the same horizontal planes as said groove and having its side wall adjacent said groove and having its bottom slightly lower than the bottom of said groove.

5. In a combined distillate and power burner, a burner base having coaxial communicating inner and outer distillate burner grooves and axial communicating power burner pressure air and flame passage forming means and having the latter extending above the base and within said distillate burner, a power burner vaporizing chamber maintained at a fuel vaporizing temperature by said distillate burner and surround-

ing said air passage means and delivering into said flame passage means, and a distillate burner vaporizing chamber eccentrically disposed with respect to said power burner vaporizing chamber and outside the lateral limits of said inner groove and communicating with said grooves.

6. In a combined distillate and power burner, a burner base having coaxial communicating inner and outer distillate burner grooves and axial communicating power burner pressure air and flame passage forming means and having the latter extending above the base and within said distillate burner, a power burner vaporizing chamber maintained at a fuel vaporizing temperature by said distillate burner and surrounding said air passage means and delivering into said flame passage means, and a distillate burner vaporizing chamber disposed between said grooves and communicating therewith.

7. In a combined distillate and power burner, a burner base having coaxial communicating inner and outer distillate burner grooves, a vaporizing chamber for supplying vaporized fuel to said grooves and located outside the lateral limits of said inner groove and air supply passage means extended upwardly through said base, axially disposed communicating power burner flame and pressure air passage forming means and having the former extending above the base and within said distillate burner, a power burner vaporizing chamber maintained at a fuel vaporizing temperature by said distillate burner and surrounding said air passage means and communicating with said flame passage means and having a wide bottom, and a baffle ring overlying the chamber top in said flame passage means above both said chamber and air passage means and having an axial opening at least as large as said air supply passage means.
